SOUND REPRODUCING APPARATUS

Samuel S. Sempre, Bronx, N. Y.

Application February 11, 1939, Serial No. 255,801

3 Claims. (Cl. 274—14)

This invention relates to sound reproducing devices and has for an object the provision of improvements in this art. A specific form of the invention has been developed as a toy novelty in the semblance of a common type of telephone stand and the invention will be described in connection with this embodiment, though with the understanding that the invention may be embodied in commercially useful forms as well as toys and also that it may be embodied in forms which depart in various ways from the one which has been selected for illustration herein.

According to this invention a sound reproducing device is arranged to be set into operation for rendering a selection from a record whenever an ear phone or receiver is removed from its holder. Moreover, mechanism is provided for insuring that the selection will be reproduced from the beginning each time the receiver or ear phone is taken up. This may be accomplished by automatically moving the needle of the microphone or the sound pick-up box to a zero or predetermined starting position when the receiver is replaced on its holder.

In the accompanying drawings illustrating the selected embodiment of the invention:

Fig. 1 is an elevational view with the receiver on its holder;

Fig. 2 is a similar view with the cover raised and the receiver removed from its holder;

Fig. 3 is a perspective view with the cover raised;

Fig. 4 is a plan view, partly in section, showing the needle and microphone in starting position relative to the record;

Fig. 5 is a vertical section through the receiver holder shown in Fig. 1; and

Fig. 6 is a vertical elevational view, partly in section, on the line 6—6 of Fig. 4.

As shown in the drawings, the device comprises a casing 10 including the base 10a and the cover 10b. The cover is secured to the base by a hinge 11, and also when closed, by a lock 12. A turn-table 13, driven by any suitable means disposed within a box 14, is secured in the base 10a. The driving means may consist of a spring motor or an electrical motor, depending upon the anticipated facilities available and the price for which the set is to be sold. In the drawings a disc record 15 is shown on the turntable in position for playing.

The cover 10b carries a sound pick-up box 18, having a needle 19, the box being secured to a swingable arm 20 hinged upon a vertical axis 21. The box may be the usual type of sound box or

5 may be an electrical microphone pick-up, depending on whether pneumatic or electrical transmission is employed. In the present instance it is arranged that pneumatic transmission be used and the sound box 18 is accordingly provided with a nipple 22 for a flexible tube 23 leading outward to the nipple of a tubular bushing 24 in the cover. A flexible tube 25 is connected to the outer end of the bushing. The tube 25 may be covered by a fabric braid, if desired, to improve its appearance and strength and to take wear. The tube 25 leads to an earpiece 26 of a receiver or hand set 27. When not in use the receiver may rest in the forks of a support 28 10 secured to the top of the cover 10b.

15 Means are provided for shifting the needle and pick-up box back to the outer or starting edge of the record in an automatic manner. This may be accomplished in connection with the removal and 20 replacement of the receiver on its support. Referring to Fig. 5 a plate 30 carried by a rod 31 is disposed between the forks of the support 28 in position to form a rest for the receiver 27. The rod 31 is urged upward by a spring 32 and is limited in its upward movement by the engagement of a flange 33 on the rod coming into engagement with a shoulder in the bore which takes the rod and spring. The weight of the receiver causes the plate 30 and rod 31 to move downward 25 and the spring 32 causes them to move upward when the receiver is removed from its support.

30 The lower end of the rod 31 carries a conical plug 36 which on one side is flattened or provided with a flat plate 37 which acts as a cam in the vertical movements of the rod 31. The cam plate 37 acts upon the upper end of a brake-and-reset lever 38 swingably mounted in a bracket 39 secured within the cover 10b. Near its lower end, the lever 38 carries a reset rod 40, provided 35 with a bent end which extends beneath the pick-up box 18. For smoother action the box 18 may be provided with a raised rib 41 to cooperate with the rod 40. The inner end of the rod 40 is provided with a stop member 42 for limiting the inward movement of the box. The outward movement of the box may be limited by striking the inside of the cover.

40 When the cam plate 37 is pushed down, as by replacement of the receiver on its support, the upper end of the lever 38 is pushed outward and the lower end is pushed inward. The inward movement of the lower end of the lever raises the bent end of the rod 40 beneath the box 18 and raises the box from the record. This action also 45 causes the free inner end of the rod 40 to be

raised higher than the elbow end of this section or length of the rod, thus forming an inclined track sloping toward the outer edge of the record. This is clearly shown in Fig. 6. The rib 41 of the box 18 therefore rides down the rod 40 until the box strikes the inside of the cover 10b. This places the needle 19 in correct position to engage the starting portion of the sound track groove in the record when the needle is again lowered. It will be lowered as soon as the receiver is raised from its support to permit the cam plate 37 to move upward and the upper end of the lever 38 to move inward, the lower end of the lever to move outward, and the rod 40 to move downward.

Means are provided for starting the turntable 13 and record 15 into rotation when the receiver is removed from its support. The means herein shown for this purpose comprises a brake element 45, which may be provided with friction material 46 adapted to engage the outer edge of the turntable 13, as shown in Fig. 4. In the present embodiment the brake element 45 is formed integrally with the lower end of the lever 38. It will be obvious that when the lower end of the lever 38 is moved inward when the receiver is replaced on its support and the pick-up box 18 is moved on the raised and inclined rod 40 to its outer or starting position, the brake element 46 is forced toward the side of the turntable 13 to stop its rotation; and when the lower end of the lever 38 is moved outward when the receiver is removed from its support and the rod 40 and box 18 are lowered, the brake will be released and the turntable and record will commence their rotation. When the upper end of the lever 38 is released from the cam plate 37, both the weight of the pick-up box on the rod 40 and the rotational tendency of the turntable 13 combine to move the lower end of the lever 38 outward to release the brake and lower the rod 40 clear of the bottom of the box 18.

As previously noted, the apparatus may take various forms, the present form being selected as one which will be attractive to children. It may be ornamented on the exterior by pictures or designs suitable to the place and occasion for which it is adapted to be sold, whether for Christmas, Easter, birthdays, for souvenirs of fairs, or the like.

It is to be noted that while the casing is provided with a dial 50 and the hand-piece or receiver 27 is provided with a part 51 which appears to be a voice transmitter, these parts have no function in the actual operation of the present form of apparatus, their presence being entirely a matter of appearance, and in the latter case of balance for the hand-piece or receiver.

While the device has been considered primarily as a toy or souvenir adapted to be sold at a relatively low price, it will be understood that the principles of the invention may be applied to practical commercial uses, if desired.

It will also be understood that the invention

may be variously embodied within the limits of the prior art and the scope of the subjoined claims.

I claim as my invention:

- 5 1. Sound reproducing apparatus, comprising in combination, a casing base, a record support and driving means mounted in said base, a casing cover hinged to said base, a sound pick-up box hinged to said cover in position for its needle to operate in the sound track of a record placed on said record support, a sound receiver, flexible means for connecting said box with said receiver, a support for said receiver comprising a spring-pressed plunger having an inclined cam-plate on its lower end, a brake-and-reset lever hinged to said cover and having its upper end in working engagement with said cam-plate, a brake element on the bottom end of said lever, a re-set rod on the bottom of said lever and disposed under said box, said rod being lifted and inclined when the receiver is placed on its support to raise said box and shift it to starting position, and said brake element also being actuated at the same time to press against the side of said turntable.
- 10 2. Apparatus as set forth in claim 1 which further comprises a stop on the inner end of said re-set rod for limiting the inward travel of the box, and cooperating means between said box and the inside of said cover for limiting the outward travel of the box.
- 15 3. Sound reproducing apparatus, comprising in combination, a turntable for rotating a sound record, a sound pick-up device mounted in co-operative relationship to said record, a receiver connected by flexible means with said device and provided with a support on said apparatus, and means for re-setting said device at starting position on said record and stopping the rotation of said turntable each time the receiver is replaced on its support, and for lowering the device upon the record when the receiver is next removed from its support, whereby to reproduce the selection on the record from the beginning each time the receiver is taken for use, said re-setting means comprising a movable plunger forming part of the support for said receiver, a lever operated by said plunger, a re-set rod carried by said lever and disposed beneath said device, said rod being raised and inclined to lift said device and cause it to slide back to starting position when the receiver is placed on its support, and a brake arm also carried by said lever which is pressed against the side of the turntable when the receiver is placed on its support, said turntable and record being carried on one assembly and the other parts being carried by a separate assembly which is hinged to and removable from the first assembly, the pick-up device being swingably mounted on its assembly to move to starting position when its assembly is swung up, and the parts being associated in proper operative relationship when said assemblies are positioned together.
- 20 4. Sound reproducing apparatus, comprising in combination, a turntable for rotating a sound record, a sound pick-up device mounted in co-operative relationship to said record, a receiver connected by flexible means with said device and provided with a support on said apparatus, and means for re-setting said device at starting position on said record and stopping the rotation of said turntable each time the receiver is replaced on its support, and for lowering the device upon the record when the receiver is next removed from its support, whereby to reproduce the selection on the record from the beginning each time the receiver is taken for use, said re-setting means comprising a movable plunger forming part of the support for said receiver, a lever operated by said plunger, a re-set rod carried by said lever and disposed beneath said device, said rod being raised and inclined to lift said device and cause it to slide back to starting position when the receiver is placed on its support, and a brake arm also carried by said lever which is pressed against the side of the turntable when the receiver is placed on its support, said turntable and record being carried on one assembly and the other parts being carried by a separate assembly which is hinged to and removable from the first assembly, the pick-up device being swingably mounted on its assembly to move to starting position when its assembly is swung up, and the parts being associated in proper operative relationship when said assemblies are positioned together.
- 25 5. Sound reproducing apparatus, comprising in combination, a turntable for rotating a sound record, a sound pick-up device mounted in co-operative relationship to said record, a receiver connected by flexible means with said device and provided with a support on said apparatus, and means for re-setting said device at starting position on said record and stopping the rotation of said turntable each time the receiver is replaced on its support, and for lowering the device upon the record when the receiver is next removed from its support, whereby to reproduce the selection on the record from the beginning each time the receiver is taken for use, said re-setting means comprising a movable plunger forming part of the support for said receiver, a lever operated by said plunger, a re-set rod carried by said lever and disposed beneath said device, said rod being raised and inclined to lift said device and cause it to slide back to starting position when the receiver is placed on its support, and a brake arm also carried by said lever which is pressed against the side of the turntable when the receiver is placed on its support, said turntable and record being carried on one assembly and the other parts being carried by a separate assembly which is hinged to and removable from the first assembly, the pick-up device being swingably mounted on its assembly to move to starting position when its assembly is swung up, and the parts being associated in proper operative relationship when said assemblies are positioned together.
- 30 6. Sound reproducing apparatus, comprising in combination, a turntable for rotating a sound record, a sound pick-up device mounted in co-operative relationship to said record, a receiver connected by flexible means with said device and provided with a support on said apparatus, and means for re-setting said device at starting position on said record and stopping the rotation of said turntable each time the receiver is replaced on its support, and for lowering the device upon the record when the receiver is next removed from its support, whereby to reproduce the selection on the record from the beginning each time the receiver is taken for use, said re-setting means comprising a movable plunger forming part of the support for said receiver, a lever operated by said plunger, a re-set rod carried by said lever and disposed beneath said device, said rod being raised and inclined to lift said device and cause it to slide back to starting position when the receiver is placed on its support, and a brake arm also carried by said lever which is pressed against the side of the turntable when the receiver is placed on its support, said turntable and record being carried on one assembly and the other parts being carried by a separate assembly which is hinged to and removable from the first assembly, the pick-up device being swingably mounted on its assembly to move to starting position when its assembly is swung up, and the parts being associated in proper operative relationship when said assemblies are positioned together.
- 35 7. Sound reproducing apparatus, comprising in combination, a turntable for rotating a sound record, a sound pick-up device mounted in co-operative relationship to said record, a receiver connected by flexible means with said device and provided with a support on said apparatus, and means for re-setting said device at starting position on said record and stopping the rotation of said turntable each time the receiver is replaced on its support, and for lowering the device upon the record when the receiver is next removed from its support, whereby to reproduce the selection on the record from the beginning each time the receiver is taken for use, said re-setting means comprising a movable plunger forming part of the support for said receiver, a lever operated by said plunger, a re-set rod carried by said lever and disposed beneath said device, said rod being raised and inclined to lift said device and cause it to slide back to starting position when the receiver is placed on its support, and a brake arm also carried by said lever which is pressed against the side of the turntable when the receiver is placed on its support, said turntable and record being carried on one assembly and the other parts being carried by a separate assembly which is hinged to and removable from the first assembly, the pick-up device being swingably mounted on its assembly to move to starting position when its assembly is swung up, and the parts being associated in proper operative relationship when said assemblies are positioned together.
- 40 8. Sound reproducing apparatus, comprising in combination, a turntable for rotating a sound record, a sound pick-up device mounted in co-operative relationship to said record, a receiver connected by flexible means with said device and provided with a support on said apparatus, and means for re-setting said device at starting position on said record and stopping the rotation of said turntable each time the receiver is replaced on its support, and for lowering the device upon the record when the receiver is next removed from its support, whereby to reproduce the selection on the record from the beginning each time the receiver is taken for use, said re-setting means comprising a movable plunger forming part of the support for said receiver, a lever operated by said plunger, a re-set rod carried by said lever and disposed beneath said device, said rod being raised and inclined to lift said device and cause it to slide back to starting position when the receiver is placed on its support, and a brake arm also carried by said lever which is pressed against the side of the turntable when the receiver is placed on its support, said turntable and record being carried on one assembly and the other parts being carried by a separate assembly which is hinged to and removable from the first assembly, the pick-up device being swingably mounted on its assembly to move to starting position when its assembly is swung up, and the parts being associated in proper operative relationship when said assemblies are positioned together.
- 45 9. Sound reproducing apparatus, comprising in combination, a turntable for rotating a sound record, a sound pick-up device mounted in co-operative relationship to said record, a receiver connected by flexible means with said device and provided with a support on said apparatus, and means for re-setting said device at starting position on said record and stopping the rotation of said turntable each time the receiver is replaced on its support, and for lowering the device upon the record when the receiver is next removed from its support, whereby to reproduce the selection on the record from the beginning each time the receiver is taken for use, said re-setting means comprising a movable plunger forming part of the support for said receiver, a lever operated by said plunger, a re-set rod carried by said lever and disposed beneath said device, said rod being raised and inclined to lift said device and cause it to slide back to starting position when the receiver is placed on its support, and a brake arm also carried by said lever which is pressed against the side of the turntable when the receiver is placed on its support, said turntable and record being carried on one assembly and the other parts being carried by a separate assembly which is hinged to and removable from the first assembly, the pick-up device being swingably mounted on its assembly to move to starting position when its assembly is swung up, and the parts being associated in proper operative relationship when said assemblies are positioned together.
- 50 10. Sound reproducing apparatus, comprising in combination, a turntable for rotating a sound record, a sound pick-up device mounted in co-operative relationship to said record, a receiver connected by flexible means with said device and provided with a support on said apparatus, and means for re-setting said device at starting position on said record and stopping the rotation of said turntable each time the receiver is replaced on its support, and for lowering the device upon the record when the receiver is next removed from its support, whereby to reproduce the selection on the record from the beginning each time the receiver is taken for use, said re-setting means comprising a movable plunger forming part of the support for said receiver, a lever operated by said plunger, a re-set rod carried by said lever and disposed beneath said device, said rod being raised and inclined to lift said device and cause it to slide back to starting position when the receiver is placed on its support, and a brake arm also carried by said lever which is pressed against the side of the turntable when the receiver is placed on its support, said turntable and record being carried on one assembly and the other parts being carried by a separate assembly which is hinged to and removable from the first assembly, the pick-up device being swingably mounted on its assembly to move to starting position when its assembly is swung up, and the parts being associated in proper operative relationship when said assemblies are positioned together.
- 55 11. Sound reproducing apparatus, comprising in combination, a turntable for rotating a sound record, a sound pick-up device mounted in co-operative relationship to said record, a receiver connected by flexible means with said device and provided with a support on said apparatus, and means for re-setting said device at starting position on said record and stopping the rotation of said turntable each time the receiver is replaced on its support, and for lowering the device upon the record when the receiver is next removed from its support, whereby to reproduce the selection on the record from the beginning each time the receiver is taken for use, said re-setting means comprising a movable plunger forming part of the support for said receiver, a lever operated by said plunger, a re-set rod carried by said lever and disposed beneath said device, said rod being raised and inclined to lift said device and cause it to slide back to starting position when the receiver is placed on its support, and a brake arm also carried by said lever which is pressed against the side of the turntable when the receiver is placed on its support, said turntable and record being carried on one assembly and the other parts being carried by a separate assembly which is hinged to and removable from the first assembly, the pick-up device being swingably mounted on its assembly to move to starting position when its assembly is swung up, and the parts being associated in proper operative relationship when said assemblies are positioned together.
- 60 12. Sound reproducing apparatus, comprising in combination, a turntable for rotating a sound record, a sound pick-up device mounted in co-operative relationship to said record, a receiver connected by flexible means with said device and provided with a support on said apparatus, and means for re-setting said device at starting position on said record and stopping the rotation of said turntable each time the receiver is replaced on its support, and for lowering the device upon the record when the receiver is next removed from its support, whereby to reproduce the selection on the record from the beginning each time the receiver is taken for use, said re-setting means comprising a movable plunger forming part of the support for said receiver, a lever operated by said plunger, a re-set rod carried by said lever and disposed beneath said device, said rod being raised and inclined to lift said device and cause it to slide back to starting position when the receiver is placed on its support, and a brake arm also carried by said lever which is pressed against the side of the turntable when the receiver is placed on its support, said turntable and record being carried on one assembly and the other parts being carried by a separate assembly which is hinged to and removable from the first assembly, the pick-up device being swingably mounted on its assembly to move to starting position when its assembly is swung up, and the parts being associated in proper operative relationship when said assemblies are positioned together.

SAMUEL S. SEMPRE.
